UNITED STATES PATENT OFFICE.

CARL J. HAZELTON, OF WORCESTER, MASSACHUSETTS, ASSIGNOR TO AMERICAN NARROW FABRIC COMPANY, OF WORCESTER, MASSACHUSETTS, A CORPORATION OF MASSACHUSETTS.

HOSE-SUPPORTER BUTTON.

Application filed March 11, 1922. Serial No. 543,061.

To all whom it may concern:

Be it known that I, CARL J. HAZELTON, a citizen of the United States, residing at Worcester, in the county of Worcester and 5 State of Massachusetts, have invented a new and useful Hose-Supporter Button, of which the following is a specification:

This invention relates to a button for hose supporters. The principal objects of 10 the invention are to provide improved and simplified means for attaching a rubber collet to a base of sheet metal or other material; to provide the attaching means in such form as to positively prevent the turning of the 15 rubber collet on its axis even after considerable wear; and to provide a fastening device which will be capable of passing through the collet and holding it effectively, and will keep the outer surface of 20 the head of the collet in a smooth uninterrupted form. Additional objects and advantages of the invention will appear hereinafter.

Reference is to be had to the accompanying drawings, in which—

Fig. 1 is a front view of a hose supporter having a button constructed in accordance with this invention;

Fig. 2 is a central longitudinal sectional view of the same on the line 2—2 of Fig. 1;

Fig. 3 is a transverse sectional view on the line 3—3 of Fig. 1;

Fig. 4 is a longitudinal central sectional view showing a modified form;

Fig. 5 is a similar view showing another modification, and

Fig. 6 is a front view of the latter.

It has been usual to fasten rubber collets on their bases by means of a central cylindrical headed rivet passing through the same and riveted over on the back of the supporting plate or base. When these collets are round they sometimes get loose after long wear and are capable of rotating or 45 turning on the rivet as a center. This is not a serious disadvantage in the case of round collets, but would spoil the efficiency of a collet which was given some other shape in order to improve its function of holding

50 the top of a stocking and this invention is shown as applied to a button of that type.

For the purpose of illustration I have shown the invention as applied to a button

having an oblong head in which the longer diameter is transverse to the length of the 55 hose supporter.

Referring to the first three figures I have shown a flat metal base plate 10 over which the narrow fabric 11 passes, and to which it is attached in any usual way. On this plate 60 is carried a collet 12 of soft rubber. This collet has an oblong head with its axis horizontal or transverse to the length of the hose supporter, and is provided with a shank shown as smaller in diameter than the head 65 so that the wire loop 14 will pass under the projecting surfaces of the head and hold the fabric of the stocking to the collet.

For the purpose of fastening this collet in position I provide a staple like member 70 16 made of a piece of flat wire preferably, and having a long head 17 doubled under at both ends to form ends 18 of double thickness and having its two ends bent downwardly therefrom to form two fastening 75 prongs 19. These are both passed through corresponding holes in the base plate and riveted over on the back. This staple, of course, passes through two perforations through the collet which are spaced 80 apart and between which there is a solid body 20 of rubber integrally united with the rest of the collet. The head of the staple is located flush with the head of the collet so as to form a complete unitary structure and 85 leave the visible surface of this head in a substantially smooth condition without any material indentation. The staple is made of metal, preferably enameled, the same color as the rubber collet, so that these two 90 parts present a similar appearance and there is no indication of incongruity. This constitutes a firm collet and prevents all chance of the collet being turned on its axis even after long wear, so that any advantage secured by making the collet oblong will 95 always be maintained as long as the same is in use.

In the form shown in Fig. 4 the same principles are maintained except that there 100 are two separate rivets 21 instead of one, and the two heads 22 of the rivets are formed in such a way as to make, as nearly as possible, a continuous metal plate on the top of the collet.

In the last two figures I have shown a

similar construction in which there is a single rivet passing through the collet having a flat head 26 shaped and located similar to the others mentioned above, and provided with a flat shank 27 extending down to the base plate and passing through a similar shaped hole therein and riveted over on the back. The shape of the collet is somewhat changed in this form, which will show 10 that the invention is not limited to the form shown in the first three figures.

In each of these forms the metallic staple or staples can be enameled as above described and the extreme ends of the staple shanks are shouldered for an obvious purpose. Different shapes of the collets are shown merely to indicate the fact that the 15 invention is applicable in different forms.

Although I have illustrated and described 20 three forms of the invention I am aware of the fact that other modifications can be made therein by any person skilled in the art without departing from the scope of the invention as expressed in the claims. There- 25 fore, I do not wish to be limited to all the

details of construction herein shown and described, but what I do claim is:—

1. As an article of manufacture a hose supporter button comprising an oblong rubber collet, and a staple for securing it in 30 position, said staple having a flat head extending longitudinally of the button at its outer surface and flush therewith, and two legs spaced apart extending through the rubber to the rear thereof. 35

2. As an article of manufacture, a hose supporter button comprising a rubber collet, and a staple for securing it in position, said staple having a flat head extending longitudinally of the button at its outer 40 surface, and two legs spaced apart extending through the rubber to the rear thereof, the staple being made of flat wire and being bent inwardly under the ends of the head to form a double thickness and the legs projecting down from the inner ends of the double thickness. 45

In testimony whereof I have hereunto affixed my signature.

CARL J. HAZELTON.
